UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

OSCILLATING-CURRENT GENERATOR.

1,329,758.

Specification of Letters Patent.

Patented Feb. 3, 1920.

Original application filed March 26, 1915, Serial No. 17,225. Patent No. 1,221,034. Divided and this application filed June 16, 1916. Serial No. 104,074.

To all whom it may concern:

Be it known that I, LEE DE FOREST, a citizen of the United States, and residing at New York, county of Bronx, State of New York, have made a certain new and useful Invention in Oscillating - Current Generators, of which the following is a specification.

This invention relates to oscillating current generators and is subject matter divided from my copending application, which has since issued on April 3d, 1917, as Letters Patent No. 1,221,034.

The object of the invention is to provide a high frequency oscillating current generator which is simple and efficient.

Other objects of the invention will appear more fully hereinafter.

The invention consists substantially in the construction, combination, location and relative arrangement of parts all as will be more fully hereinafter set forth, as shown in the accompanying drawings, and finally pointed out in the appended claim.

Figure 1 is a circuit diagram showing one arrangement embodying my invention.

Figs. 2 and 3 are modified constructions of oscillation generators embodying my invention.

Fig. 4 is a sectional view taken on the line 4, 4, Fig. 1, and looking in the direction of the arrows.

Referring to the drawings,—

1 designates generally an evacuated vessel which is provided with two chambers 2 and 3 which are united by a narrow passage 4. In these two chambers I place electrodes, which may be of any desirable material, but for illustrative purposes, I have shown the same to be of mercury or an amalgam thereof at 5, 6. A source of electromotive force, indicated at 7, supplies a current through a variable resistance 8 to the electrodes 5, 6, to heat the same and cause a vapor arc column to form in the passage 4.

In a chamber 3^a, forming part of the evacuated vessel 1 and communicating with the mercury arc passage 4, are located two cold electrodes 9 and 10, preferably arranged at different distances from the vapor arc column maintained in the passage 4.

The electrode 9 is electrically connected to one terminal of a source of electromotive

force 11. I have found it preferable to employ a direct current generator, as shown, but my invention is not to be limited thereto. One terminal of the current source 11 is connected to an electrode 9, and the other terminal of said current source 11 is connected to one of the cathode electrodes of the evacuated vessel, as, for instance, the electrode 5. The circuit connection between electrode 9 and source 11, preferably contains an "inertia" coil indicated at 12.

It is of advantage to maintain the electrodes 9 and 10, cool, and this may be accomplished in any suitable convenient manner.

In the case of electrode 9 I have shown a simple arrangement wherein I employ a reservoir 13 which is provided with pipes 14 opening upon the electrode 9 and adapted to allow a cooling medium such as air, water, oil, or the like, to circulate therethrough.

The electrode 10 may be of any desired shape, or material, but I have found it advantageous to employ therefor a bent hollow grid.

As shown in Fig. 1, the electrode 10 is a bent hollow grid with extensions projecting out of said evacuated vessel 1 to allow a cooling medium to circulate therethrough. The cooling medium may be supplied from reservoir 13, and for the sake of avoiding confusion in the drawing the connections between the electrode 10 and reservoir 13 have been omitted. My invention, however, is not to be limited or restricted in this respect.

In the usual and well known way, I associate an oscillating circuit with the two cold electrodes 9 and 10. This circuit consists of the usual condenser 15, and inductance 16, arranged in series with electrodes 9 and 10 and with each other. If desired, and as shown, a switch or other form of circuit make and break device 17 may also be placed in series in this oscillating circuit. If desired, and as shown, a variable capacity, such as a condenser 18, may be shunted around the inductance 16, but my invention in its broad scope is not to be limited or restricted to this detail.

I propose to connect a high resistance 19 to the electrode 10 and the vapor arc column maintained in the passage 4, to form a high resistance "leak" path between said electrodes. The purpose of this leak path

is to conduct off the excessive charge which may accumulate on the electrode 10 and thereby reduce the efficient operation of the oscillator.

5 I have discovered that if a second oscillating circuit be established including therein the electrode 9 and the vapor arc maintained in the passage 4, the inductance 20 and condenser 21 all in series with each 10 other the oscillations set up in the original oscillating circuit 9, 16, 18, 15, 10 are increased in intensity provided the period of the second oscillating circuit is made equal to that of the first oscillating circuit. It is 15 not essential, however, to employ this second oscillating circuit, and my invention, therefore, as defined by the claim, is not to be limited or restricted in this respect; therefore, the elements 20, 21 may be omitted 20 if desired. When the two oscillating circuits are employed, however, the inductance elements 16, 20, thereof, should be inductively associated, as shown.

A "load" or output circuit may be associated, either inductively or conductively 25 with one or both of the above described oscillating circuits. In the arrangement shown, the load circuit is made up of a variable inductance 22 connected intermediate 30 the radiating antenna 23 and the ground or earth 24 in the usual and well known manner for radio operation. The natural period of the load circuit should be equal to that of the first or original oscillating circuit.

35 In Fig. 2 I show a modified form of evacuated vessel oscillator, wherein the heated electrode may be a filament instead of a vapor arc above described. In this form of my invention the cold electrode 10^a 40 is shown in section as a metal tube inserted in the constricted portion of the chamber 3^a of the vessel 1, immediately above the passage 4. Instead of employing a column of vapor, if desired, and as shown, a heavy filament 45 of tungsten, or platinum coated with oxid of calcium or other suitable material may be employed as indicated at 25. In this instance, heavy "leading in" wires 26 are employed to support the heating filament 25. 50 The circuit connections and the operation of this modification of my invention is similar to the above described arrangement shown in Fig. 1.

If desired, instead of employing the mercury or other form of electrodes 6, 5 in chambers 2, 3 of Fig. 1, or the filament arrangement of Fig. 2, one of the chambers 2, 3, may be supplied with a mercury or other form of electrode such as 5 or 6, while the 60 other associated chamber may be provided with a suitable non-vaporizable electrode such as indicated at 27, Fig. 3.

The exact operation involved in a generator having the construction shown in the drawing, and as above described I have not

as yet been able to fully and completely understand. I have discovered, however, that such an arrangement or arrangements do operate as a generator of high frequency oscillations suitable for radio work, and, 70 whether correct or not the oscillatory phenomena involved in the operation of the apparatus may be described in a general way as follows:

If the generator 11 is a direct current 75 source a negative current is set up across the oscillator by means of the thermions passing from the hot electrode 25, 27, or the vapor arc in passage 4 as the case may be, to the cold electrode 9. A negative charge 80 impressed upon the cold electrode 10 will greatly reduce the flow of thermions from the hot electrode or vapor arc to the electrode 9, or, in other words, will increase the potential drop between the cold electrode 9 85 and the hot electrode. Therefore, if the electrical connection between the electrode 10 and the electrode 9 be suddenly established by closing the switch or circuit maker 17, the positive potential of the electrode 9 90 and of the positive terminal of condenser 18 will be suddenly increased. Further, any positive charge on the electrode 10 will be rapidly carried away by action of the negatively charged thermions from the hot electrode 95 attracted thereto, inasmuch as the capacity of the "stopping" condenser 15 is small. Thus a difference in potential is quickly established between the two terminals of condenser 18. The inductance coil 100 16 prevents this difference of potential across the condenser 18 from immediately equalizing and in consequence an oscillatory discharge is set up through the inductance 16. At the end of a half period of this discharge the potential of one armature of the condenser 18 is therefore reduced or made negative, while that on the other side of the condenser is made positive relative thereto. The reduction of the positive potential at one 110 terminal of condenser 18, and on the electrode 9 causes a sudden increase of positive current from source 11 which again charges one terminal of condenser 18 positively, and a negative current again sets up across coil 115 16 to the other terminal of said condenser and to the electrode 10. This inrush of negative charge to the electrode 10 will again reduce the passage of thermions from the hot electrode to the cold electrode 9, that is, will 120 again still further increase the positive potential of 9 and the corresponding terminal of condenser 18 relative to the other terminal of said condenser. Thus condenser 18 will once more begin to discharge a positive 125 current through the coil 16 and the entire phenomenon as above described, will be repeated, growing in intensity as it proceeds, due to the electro-magnetic inertia of coil 16, up to a point where the losses in the cir- 130

cuits and in the oscillator are equal to any further increase in the energy representing the oscillations.

Having now described the objects and nature of my invention, and various arrangements for accomplishing the same, what I claim as new and useful and desire to secure by Patents, is,—

In an audion structure, the combination 10 with an evacuated vessel, of a hot electrode

and a plate electrode located within said vessel, and a hollow grid shaped electrode also located within said vessel and interposed between said hot and plate electrodes, to permit a cooling fluid to be passed through said grid electrode from the exterior of said vessel.

In testimony whereof I have hereunto set my hand on this 5th day of June, A. D., 1916.

LEE DE FOREST.
